HEEL-CAP PRESS

Charles L. Sien, Anaheim, Calif.

Application September 30, 1938, Serial No. 232,668

3 Claims. (Cl. 12—125)

This invention aims to provide a simple but efficient device for holding a heel cap on the heel of a shoe, during the assembling of the heel cap with the heel of the shoe.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in elevation, a device constructed in accordance with the invention;

Fig. 2 is a side elevation at right angles to the showing of Fig. 1, parts being in the positions which they will assume during the operation of clamping the heel cap to the heel of a shoe;

Fig. 3 is a section on the line 3—3 of Fig. 1; Fig. 4 is a section of the stop.

In carrying out the invention there is supplied a first frame 1, comprising parallel side arms 2, provided at their upper ends with converging pieces 3, which are twisted together as shown at 4, and continued to form an eye 5, which is adapted to be detachably assembled with a hook 6 on any convenient object 7, the converging pieces 3 forming the upper member of the frame 1. By means of securing elements 8, the lower ends of the side arms 2 of the first frame 1 are connected to a rigid lower member or foot plate 9 equipped with parallel slots 10 located in planes parallel to the plane in which the arms 2 lie.

The numeral 11 marks a depending, inwardly-inclined stop having a rounded lower end 12, the stop 11 and its end 12 being so constructed that they will not damage a shoe heel. At its upper end, the stop 11 has an attaching flange 14, fastened on top of the foot plate 9 of the frame 1 by one of the securing elements 8, and by any desired number of additional securing elements 15. The stop 11 is concaved transversely, as shown at 16, to fit properly, the transverse curve of the shoe heel. A resilient pad 17, which may comprise an upper layer of leather or the like, and a lower layer of resilient rubber or similar material, is secured to the lower surface of the

foot plate 9, and the elements 9 and 17 form a heel-engaging part.

A second frame 18 is supplied, the frame 18 being located in a plane at right angles to the plane that is occupied by the first frame 1. The second frame 18 comprises side arms 19, a lower member or cross bar 20, and an upper member or top plate 21. The arms 19 of the second frame are mounted to move longitudinally and transversely in the elongated slots 10 of the foot plate 9 of the first frame 1. The lower member 20 of the second frame 18 carries stops 22. An abutment bracket 23 is provided, and its side arms are mounted to swing on the lower member 20 of the frame 18. The stops 22 prevent the abutment bracket 23 from moving lengthwise of the lower member of the frame 18. The abutment bracket 23 includes a head plate 24.

A pressure-exerting device, for example a screw 25, is threaded into the top plate 21 of the second frame 18. The pressure screw 25 is connected by a ball and socket joint 26 to a plate-like slide 27. The slide 27 is provided with slots, like the slots 10 of the plate 9, and the said slots of the slide receive the side arms 19 of the second frame 18. A compression spring 28 is supplied, the upper end of the compression spring being connected by a securing means 29 to the slide 27. The lower end of the compression spring 28 is attached by a securing means 30 to the foot plate 9 of the first frame 1.

The screw 25 can be backed out as much as desired, to ease off the pressure on the spring 28. The head plate 24 of the abutment bracket 23 is placed against the inside sole of the shoe, and the shoe is swung inwardly, until, as shown in Fig. 2, the heel of the shoe comes into contact with the stop 11. The screw 25 is operated to compress the spring 28, relative longitudinal movement between the frames 1 and 18 will take place, and the pad 17 will be pressed the more tightly on the heel cap, to hold the cap the more firmly on the shoe heel.

Owing to the fact that the slots 10 in the foot plate 9 are provided, and owing to the fact that the slide 27 has corresponding slots, the part 24 of the abutment bracket 23 and the pad 17 need not be parallel. The device, therefore, accommodates itself readily to shoes wherein, as is usual, the outer surface of the heel cap is not parallel to the inner surface of the rear portion of the sole, an observation which will be understood readily when Fig. 2 is noted. The device is simple in construction, but will be found thor-

oughly advantageous and effective for the ends in view.

What is claimed is:

1. A device for holding a cap on the heel of a shoe during the assembling of the cap with the heel, the device comprising a loop-shaped first frame and a loop-shaped second frame arranged in planes approximately at right angles to each other, each frame comprising side arms and upper and lower members connecting the side arms, the lower member of the first frame constituting a cap-engaging part, and being mounted to move on the side arms of the second frame, longitudinally on the side arms of the second frame and transversely thereof, a slide disposed between the lower member of the first frame and the upper member of the second frame and mounted to move on the side arms of the first frame, longitudinally on the side arms of the second frame and transversely of the side arms of the second frame, a compression spring interposed between the lower member of the first frame and the slide, a pressure-exerting device adjustably mounted in the upper member of the second frame and engaged with the slide, and an abutment bracket mounted on the lower member of the second frame, for swinging movement toward and away from the longitudinal axis of the second frame, to and from a position beneath the cap-engaging part, the bracket constituting means for engaging the inside of the sole of the shoe to the heel of which the cap is to be attached. 5
- 15 3. A device for holding a cap on the heel of a shoe during the assembling of the cap with the heel, the device comprising a loop-shaped first frame and a loop-shaped second frame arranged in planes approximately at right angles to each other, each frame comprising side arms and upper and lower members connecting the side arms, the lower member of the first frame constituting a cap-engaging part, and being mounted to move on the side arms of the second frame, longitudinally on the side arms of the second frame and transversely thereof, a slide disposed between the lower member of the first frame and upper member of the second frame and mounted to move on the side arms of the first frame, longitudinally on the side arms of the second frame and transversely of the side arms of the second frame, a compression spring interposed between the lower member of the first frame and the slide, a pressure-exerting device adjustably mounted in the upper member of the second frame and engaged with the slide, and an abutment means carried by the lower end of the second frame disposed below the cap-engaging part for cooperation with the inside of the sole of the shoe to the heel of which the cap is to be attached. 10
- 20 2. A device for holding a cap on the heel of a shoe during the assembling of the cap with the heel, the device comprising a loop-shaped first frame and a loop-shaped second frame arranged in planes approximately at right angles to each other, each frame comprising side arms and upper and lower members connecting the side arms, the lower member of the first frame constituting a cap-engaging part, and being mounted to move on the side arms of the second frame, longitudinally on the side arms of the second frame and transversely thereof, a slide disposed between the lower member of the first frame and the upper member of the second frame and mounted to move on the side arms of the first frame, longitudinally on the side arms of the second frame and transversely of the side arms of the second frame, a compression spring interposed between the lower member of the first frame and the slide, a pressure-exerting device adjustably mounted in the upper member of the second frame and engaged with the slide, and an abutment means carried by the lower end of the second frame disposed below the cap-engaging part for cooperation with the inside of the sole of the shoe to the heel of which the cap is to be attached. 15
